CLAIM

The ornamental design for a dehumidifier, as shown and described.

DESCRIPTION

FIG. 1 is a front perspective view of a dehumidifier showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged detail view of area 9 circumscribed in FIG. 1;

FIG. 10 is an enlarged detail view of area 10 circumscribed in FIG. 2;

FIG. 11 is an enlarged detail view of area 11 circumscribed in FIG. 3;

FIG. 12 is an enlarged detail view of area 12 circumscribed in FIG. 4;

FIG. 13 is an enlarged detail view of area 13 circumscribed in FIG. 5; and,

FIG. 14 is an enlarged detail view of area 14 circumscribed in FIG. 6.

The dash-dash lines in the figures depict portions of the dehumidifier that form no part of the claimed design. The dash-dot broken lines denote the boundaries of the enlarged detail areas and form no part of the claim.
